UNITED STATES PATENT OFFICE.

EDWARD R. CLIFF, OF NEW YORK, N. Y., ASSIGNOR OF ONE-HALF TO
FREDERICK W. WISE, OF SAME PLACE.

ELECTRIC-CURRENT-SHUNTING DEVICE.

SPECIFICATION forming part of Letters Patent No. 651,697, dated June 12, 1900.

Application filed January 4, 1900. Serial No. 363. (No model.)

To all whom it may concern:

Be it known that I, EDWARD R. CLIFF, a citizen of the United States, and a resident of New York, (New Brighton,) in the county of

5 Richmond and State of New York, have invented certain new and useful Improvements in Electric - Current - Shunting Devices, of which the following is a specification.

My invention relates to that class of devices 10 which are employed in connection with arc or incandescent lamps, or both, when arranged in series for lighting or signal purposes to shunt or short-circuit the current across the terminals or leads of a lamp or across from the out- 15 going to the incoming conductor when in the one case the lamp is burned out or in any way becomes broken or destroyed or in the other case the conductor becomes broken beyond the shunting device, its object being to pro- 20 vide a device of this character which, while simple in construction and efficient in operation, shall permit of the employment of a re- sistance in connection therewith, when de- 25 sired, to compensate for the resistance of the lamp or lamps withdrawn from operation and at the same time serve to shunt or short-cir- 30 cuit the current across the terminals or leads of the same when such resistance becomes de- stroyed or otherwise impaired.

35 To this end the invention consists in certain peculiarities of construction and arrangement of parts whereby these results are accom- plished, all as will hereinafter more fully appear.

Referring to the accompanying drawings, 40 which form a part of this specification, Figure 1 is a side elevation of a current-shunting device constructed in accordance with my invention; Fig. 2, a side elevation of a current- 45 shunting device of a slightly-modified construction; Fig. 3, a plan view thereof; Fig. 4, a longitudinal sectional elevation of my device, taken in the plane $x-x$ of Fig. 3; Fig. 5, a diagrammatic view showing the shunting 50 device employed in multiple with arc electric lamps arranged in series; Fig. 6, a similar diagrammatic view showing the device em- ployed in multiple with incandescent lamps arranged in series; and Fig. 7, a like diagram- 55 matic view showing the device arranged in

a circuit of incandescent electric lamps and extending across from the outgoing to the incoming conductor, with the lamps disposed in series.

In all the figures like letters of reference are 55 employed to designate corresponding parts.

A indicates the standards or supports in and upon which the various parts of the shunting devices are or may be mounted and operated. These standards or supports are 60 preferably constructed of electricity-non-conducting material—such, for instance, as fiber, hard rubber, or the like—and are secured together and held at the proper distance apart by any appropriate means. The means which 65 I prefer to employ for this purpose, however, consists of two rods or bars a , which, extending across from one of such standards or supports to the other, are firmly secured at their ends therein by suitable screw-threads and 70 collars, with which their respective ends are provided, and nuts a' for coöperating therewith, as shown.

Located between the standards or supports A is a contact B, which through appropriate 75 electric connections is connected with a clamping-post b or other approved device by means of which a conductor or lead may be connected therewith. This contact may be constructed in various forms. I prefer, how- 80 ever, to construct it in the form of a rod or bar from any appropriate conducting mate- rial and of a length to extend across from one of the standards or supports to the other, with a suitable threaded orifice formed in each of 85 its ends, axially of the same, whereby it may be secured in place by screws b' , passed through suitable holes formed in the upper edges of the standards or supports and en- gaging therewith. By this arrangement the 90 bar or rod, in addition to serving as an elec- tric contact, also serves as an aid to the rods or bars a in securing the standards or sup- ports together and holding them at the proper distance apart. For connecting this contact 95 B with the binding-post or terminal b any con- venient form of electric connection may be employed. In the form, however, selected by me for the purpose of illustration it con- 100 sists of a metal conducting - strip b^2 , which,

preferably secured to the outer side of one of the standards or supports A and carrying at its lower end the binding-post or other connecting appliances, is electrically connected 5 with the contact B through one of the screws b' , which passes through the strip and engages therewith. As thus disposed the contact is adapted to support a strip of paper b^3 , which in practice rests thereon and which may be 10 held in that position by any approved means. I prefer, however, to employ for that purpose the spools or rollers b^4 and b^5 , upon which its ends are respectively wound and which are journalled in bearings a^2 and a^3 , formed in the 15 standards or supports A, as shown. By this arrangement of parts the employment of a ribbon of paper is permitted, which may be unoiled from one and coiled upon the other, as the exigencies of its use may require, and 20 in order to permit of the ready removal or replacement of the strip, with its carrying-rolls, the bearings a^2 and a^3 are made in the form of open slots, which converge toward each other, with the slots in one standard or support 25 conforming to and registering with those in the other. With the parts as thus constructed the removal of the strip b^3 and its carrying-rolls is effected by simply raising the journals of the latter upward in the slots and re- 30 moving them, with the strip, from the device.

Coöperating with the contact B is a second contact C, which is adapted to bear upon the upper side of the strip b^3 . This contact may be constructed in various forms. As here 35 shown, however, it is constructed in the form of a rod which is pivoted between the standards or supports A by a shaft or rod c , that is journalled at its ends in suitable bearings c' in the standards or supports A and is pro- 40 vided with a binding-post c^2 or other clamping device that is adapted to receive and hold the extremity of an electric conductor. The contact C being thus disposed extends forward over the contact B and rests upon the 45 strip of paper through its own gravity, which may be increased, if desired, by the employ- 50 ment of a suitable weight c^3 , that may be fix- 55 edly or adjustably secured thereon. While thus bearing normally upon the upper sur- 60 face of the strip of paper b^3 , this contact may be swung upward into a vertical position, when desired, to permit of the removal of 65 such strip with its carrying spools or rollers, as shown in Fig. 3.

With the parts constructed and arranged as above explained the device may be em- 70 ployed either with an arc-lamp A' or an in- 75 candescent lamp A², as respectively shown in Figs. 5 and 6, or with a series of such lamps 80 A³, as shown in Fig. 7, in which in the one case one of the leads, as c^4 , of the lamp will be connected with the binding-post c^2 through 85 a suitable connection, as c^5 , and the other, c^6 , to the binding-post b through suitable con- 90 nections, as c^7 , while in the other case these 95 posts will be respectively connected with the

outgoing and incoming conductors A⁴ and A⁶ of the series through appropriate connections c^8 and c^9 , which respectively extend between them. As thus disposed the current passing 70 along the leads will traverse the lamp in the one case and the series of lamps in the other so long as the lamp in the one case remains intact and operative and the conductor in the other remains unbroken, in consequence of 75 the resistance afforded to the passage of the current through the shunting device by the paper strip b^3 . The moment, however, that such lamp becomes broken or otherwise in- 80 operative from any cause or either of the conductors in the series becomes broken beyond the device then the burning or perforation of the strip of paper is occasioned by the current, which is then allowed to pass through the shunting device, and the same thereby 85 shunted across the leads of the lamp or across from one conductor to the other, as the case may be.

In some instances the shunting device will be employed without any other resistance 90 than that afforded by the strip of paper b^3 , which will then be adapted to the position in which it is to be employed, and in these cases the connection of the contact B with the binding or terminal post b will preferably be 95 through the conducting-strip b^2 , as shown in Fig. 1. In other instances it will be found desirable to employ a further resistance to compensate for that of the lamp or lamps withdrawn from operation, and in such cases 100 I make use of further resistance devices, which may be constructed in any approved form—as, for instance, in that of a coil, a lamp, or the like. When made in the form of a coil, as D, I preferably support it upon 105 a bracket d , which is secured to the outer side of one of the standards or supports A, with one end of the coil connected with the contact B, through one of the screws b' or otherwise, and its other end connected with 110 the binding-post b . By this arrangement any current passing through the shunting device will be caused to traverse this resisting-coil, which in practice will preferably be made of the same or approximately the same resist- 115 ance as that of the lamp or lamps in connec- 120 tion with which it may be employed. With the resistance thus availed of I sometimes find it convenient to employ means whereby the current may be shunted across the leads 125 to and from the same when the resistance is destroyed or otherwise withdrawn from ac- 130 tion. To this end I make use of a third contact E, which, as with the contact C, may be constructed in various forms. As shown herein, 125 however, it is constructed in the form of a rod that is arranged to extend over and bear upon the upper side of the strip of paper b^3 at the side of the contact C and is preferably secured to or formed integrally with a shaft or rod e , 130 which, journalled in suitable bearings e' , that are formed in the upper corner of the stand-

ards or supports A, opposite to that in which the bearings c^2 are formed, is provided with a binding-post or terminal e^2 . The contact E, being thus pivotally mounted in the stand-
5 ards or supports A, while normally resting upon the strip b^3 , may be swung upward into the position shown in Fig. 3 to permit of the removal of such strip, with its carrying-rollers, when required, and in order to insure of its pressing thereon with the proper degree of pressure it is or may be provided at its free end with a weight e^3 , that is adjustably or fixedly secured thereto, as is the case with the weight c^3 . As thus disposed the binding-
10 post or terminal e^2 is connected with the terminal b by a conductor F, which extends from the one to the other, whereby any current passing along the contact E will be transmitted thereto and thence to and along the conductor or lead c^6 . When the parts thus specified are employed and the resistance is destroyed or rendered inoperative during the operation of the shunting device or otherwise, the current passing along the contact C from
15 the binding-post or terminal c^2 to the contact B, through the perforation in the paper strip b^3 , instead of traversing such resistance to the binding-post b and thence traveling along the lead or conductor c^6 , will pass along the
20 contact B to a point beneath the contact E, where it will burn or otherwise perforate a hole through the paper strip b^3 , and thence travel along such conductor to the binding-post or terminal e^2 , thence along the conductor or lead F to the terminal or binding-post b, and thence to and along the lead or conductor c^6 , thereby shunting the current across the leads or terminals of the resistance and establishing a circuit across from the terminal or binding-post c^2 to the terminal or binding-post b through the contacts C B E and conductor F and insuring of the operation of the other lamps in the series, as before.

When the shunting device is employed in multiple with lamps in a series and any of these lamps become broken or otherwise inoperative, the current will be shunted across the terminals of these inoperative lamps and the other lamps in the series allowed to operate and glow in precisely the same manner as when such inoperative lamps were operative. On the other hand, when a single shunting device is employed in a series of lamps and extends across from the outgoing to the incoming conductor then when one of these conductors becomes broken beyond the shunting device the current will be shunted across from one conductor to the other, thereby cutting out all lamps beyond its location and allowing all the lamps included within its circuit to continue in operation and glow as they did before the rupture of the conductor.

From the foregoing it will therefore be seen that I produce a shunting device which is capable of application in connection with the individual lamps of a series or with a number

of the lamps of a series, whereby not only the shunting of the current across the terminals of the individual lamps in the one case and across from one conductor to the other of the series in the other may be effected when any of such lamps or one of the conductors becomes broken, but the use of an appropriate compensating resistance in the circuit and the automatic shunting of the current across the terminals of the same when it becomes broken permitted.

Although in the above I have described the best means contemplated by me for carrying my invention into practice, I wish it distinctly understood that I do not limit myself strictly thereto, as it is obvious that I may modify the same in various ways without departing from the spirit of my invention—as, for instance, instead of constructing the standards or supports of the device from non-conducting material I may, if I so desire, construct them of conducting material and insulate the various operating parts of such device therefrom.

Having thus described my invention, I claim and desire to secure by Letters Patent of the United States—

1. The combination, with the standards or supports A, each of which is provided with open bearings a^2 and a^3 , a strip of non-conducting material, spools or rollers b^4 and b^5 , respectively mounted in said bearings for carrying this strip of non-conducting material, and a contact supported from the standards or supports for contact with one side of such non-conducting strip, of a second contact pivoted to the standards or supports and adapted to be swung into contact with the opposite side of the non-conducting strip to coöperate with the first-mentioned contact, or upward therefrom to permit of the removal of the non-conducting strip with its supporting spools or rollers, substantially as described.

2. The combination, with the standards or supports A, a strip of paper b^3 , the contact B fixedly secured therein and adapted to bear upon the under surface of such strip of paper, a second contact C pivoted between such standards or supports and arranged to bear upon the upper surface thereof, a binding-post or terminal for each of the contacts, and a resistance-coil D connected at one end with the fixed contact B and at the other with the binding-post or terminal for that contact, of a third contact E likewise pivoted between the standards or supports A and bearing upon the upper surface of the strip of paper opposite the contact B, and electrical connections between this contact E and the binding-post or terminal for the contact B, substantially as described.

3. The combination, with the standards or supports A provided with the open bearings a^2 and a^3 , the strip of paper b^3 , the spools or rollers b^4 and b^5 respectively mounted in such bearings for supporting this strip of paper, and the fixed contact B upon which such strip

of paper may rest; of the pivoted contacts C and E which are adapted to be swung down to rest upon the aforementioned strip of paper to coöperate with the contact B or upward therefrom to permit of the removal of such strip with its supporting spools or rollers, substantially as described.

In witness whereof I have hereunto set my hand this 28th day of December, 1899.

EDWARD R. CLIFF.
